The schedule referred to in the above Patent and making part
of the same containing a description in the words of the said Common
Number himself of his improvement in Locomotive Carriages
Rails and other Means

To all to whom these presents may come. Be it known that I
Common Number of Philadelphia in the County of Chester State
of Pennsylvania have invented a new & useful improvement in
Locomotive Carriages and that the following is a full & exact de-
scription of the construction & operation of the said improvement and
the formation of the Rail way on activities adapted thereto.

The invention consists principally in employing the power of loco-
motive engines on activities in such manner that by diminishing
the weight of the carriage the effective force of the engine will be increas-
ed in the same ratio, thereby superseding the necessity of stationary
engines. 1st a, a, are the common wheels of a locomotive carriage
(3 feet in diameter) to which the power of the engine is applied by a
shaft or crank at c, c. On these wheels the locomotive carriage
moves upon a plane drawing the train forward on the rails nearly nine
feet for every revolution. 2nd i. i. are two smaller wheels (attached
to a, a, or separate 1 foot in diameter) and placed upon the same axle
with a, a. To avoid activities the locomotive carriage moves upon
i. i. upon their own rails o, o, raising the common wheels clear from
their rails and therefore the carriage with the train moves forward
only three feet for every revolution. 3rd The diameter of the wheels
being as three to one the engine employs three times as much force
in a given space on the smaller wheels as on the common ones, but
the carriage and train move forward on the rails proportionably slow-
er. and so of wheels of any other proportions as four to one, five to one, &c.
4th On the middle of the fore axle is placed a cog wheel 3 of like di-
ameter

another with the smaller wheels to work fast in the engine, & prevent slipping on great ascents. This use of the cog wheel is known and has been variously proposed & tried. The improvement consists in substituting one cog wheel and its rail on the centre in the stead of many rails and cog wheels on both sides of locomotive carriages. 5th w. is a drag or pawl that may be attached to locomotive carriages and every car in their train to work upon the cog rail w. Its use is well known to prevent a slip or slide in case of accidents on great ascents - but it derives new importance from its connection with the cog rail w. elevated in the middle of the road. 6th The ascending rails o, e, and w. may be so constructed as to rest upon the foundations with the common rails and be raised to their proper heights by blocks, they are only used in ascending declivities and for the small wheels. The hind wheels of the locomotive carriage and the wheels of all the cars in the train run on the common rails. 7th In this specification the wheels on the fore axle only are mentioned because the power is considered as applied to the fore wheels. If the power should be applied to the hind wheels instead or in part to both fore & hind the principle would not thereby be changed. The small additional wheels on either or on both would be the application of power described & claimed as my invention.
